BATHROOM SCALE

Dana W. Mox, Glenview, Ill., assignor to Hanson Scale Company, Northbrook, Ill., a corporation of Illinois

Filed May 12, 1965, Ser. No. 85,243

Term of patent 14 years

(Cl. D52—10)

FIGURE 1 is a top plan view of the bathroom scale incorporating the instant design;

FIGURE 2 is an elevational view looking down upon FIGURE 1 from the top;

FIGURE 3 is an elevational view from the right-hand side of FIGURE 1, the left-hand side being of the same appearance; and

FIGURE 4 is an elevational view looking toward the bottom of the scale as shown in FIGURE 1.

The dominant features of the design reside in the full line portions of the scale.

I claim:

The ornamental design for a bathroom scale, as shown and described.
